Specification for Design.

Patented Nov. 24, 1914.

Application filed September 3, 1914. Serial No. 860,120. Term of patent 14 years.

To all whom it may concern:

Be it known that we, CORNELIUS E. HOLT and PROVEST R. RAUCH, citizens of the United States, residing at Washingtonville, in the county of Columbiana and State of Ohio, and Leetonia, in the county of Columbiana and State of Ohio, respectively, have invented a new, original, and ornamental Design for a Drill-Holding Head for Miners' Drills, of which the following is a specification, reference being had to the accompanying drawing, forming part thereof.

In the drawing the figure is a perspective view of the drill holding head.

We claim:

The ornamental design for a drill holding head for miners' drills, substantially as shown.

CORNELIUS E. HOLT.
PROVEST R. RAUCH.
